UNITED STATES PATENT OFFICE

CLARENCE SCHOCK, OF MOUNT JOY, PENNSYLVANIA

DISPENSING PUMP

Application filed March 16, 1928. Serial No. 262,311.

This invention relates to dispensing lift pumps and more particularly to non-measuring gasoline pumps for use in private garages, and it comprises in combination with a storage tank a pump cylinder and valve piston reciprocable therein, a discharge outlet at a low point in the pump cylinder, a loose fitting stuffing box in said cylinder at a point above the upper limit of the piston and above the discharge outlet of the pump, an upstanding pipe forming a continuation of the pump cylinder, a tubular hand grip concentrically mounted on the upstanding pipe and attached at its upper end with the upper end of the pump rod, and means below the discharge outlet of the pump permitting excess gasoline to drain back into the storage tank; all as hereinafter more specifically described and as claimed.

It is an object of my invention to provide a lift and force pump having a discharge outlet at a point lower than the receptacle to be filled and having means provided for the drainage of excess liquid from the discharge outlet and pump cylinder back to the storage tank.

It is a further object of my invention to provide a dispensing pump having a discharge outlet at a low point therein, means for preventing overflow of the liquid dispensed and means permitting return of excess liquid to the storage tank.

Other and further objects will be apparent from the following description and drawings in which:

Figure 1 is a view showing a typical installation of the pump comprising my invention, used with an underground storage tank.

Figure 2 is an elevational view, partly in vertical section, of the pump and storage tank.

Figure 3 is an enlarged fragmentary section of the pump cylinder and discharge conduit of the type of pump shown in Figure 2.

Figure 4 is a fragmentary sectional view of the upper end of the pump showing the manner of connecting the concentric hand grip with the pump rod.

Figure 5 is an enlarged sectional view of

the lower end of the pump cylinder and piston.

Figure 6 is an elevational view of a modified form of pump, wherein the storage tank is located above the surface of the ground. 55

Figure 7 is a fragmentary vertical sectional view of the discharge conduit and pump cylinder of the modified form of pump.

Figure 8 is an enlarged fragmentary section of the upper end of the upstanding pipe 60 shown in Figure 6.

Figure 9 is a sectional view of the lower end of the pump cylinder, showing a slightly modified form of my invention.

Referring more particularly to the drawings:

The pump 10 comprising the invention is designed primarily for private garage use with the intent that each car shall have its own private pump for pumping gasoline into the tank of the automobile, thus providing independent complete service for each car. The pump is adapted to be placed in the small space 11 between the doors of a double garage, where such space is not more than three or four inches in width, or inside the garage in localities where the fire regulation so permits. 70 75

Referring to Figures 2 to 5, an underground tank 12 is provided with a fill pipe 13 which projects above the level of the ground, and a pump cylinder 14 carried concentrically within a casing 15 which is screw threaded or otherwise affixed in the wall of tank 12. As is shown in Figure 3 of the drawings, casing 15 is screw threaded at its upper end and engaged with a correspondingly threaded sleeve 16 which, in turn, has a tubular sleeve 17 projecting therefrom. A T 18 is connected to the sleeve 17 and has therein a discharge opening 19. A stuffing box 20 engages the T in alignment with the sleeve 17, such stuffing box loosely engaging the rod 21 of the lift pump, to be hereinafter described. A sleeve 22 connects the stuffing box 20 with a tubular upstanding pipe 23 which extends upwardly a distance well above the stuffing box 20. A nut 24 in the upper end of the pump rod affixes a cap 25 on the rod in position to cover the upper open end of the upstanding pipe. An annular 80 85 90 95 100

flange 26 is formed on this cap, or the cap may be provided with depending ears, such flange or ears serving as a means for fastening the cap to a tubular hand piece 27 concentric with the upstanding pipe, as by means of rivets 28, also carrying a two-part clip 29 for supporting the dispensing hose 30 when it is not in use.

The pump cylinder 14, at a point above the upper limit of the pump stroke and below the discharge outlet, is formed with a hole 31 providing communication between the interior of the pump cylinder and the interior of the casing 15 which surrounds such cylinder, for a purpose to be hereinafter described.

To prevent unauthorized use of the pump an anchor 32 projects from the T and carries a chain 33 to which is affixed a slotted plate 34 adapted to receive a hasp 35 in the slot therein. A pin or padlock may then be inserted in the closed loop of the hasp to prevent reciprocation of the hand grip and consequent actuation of the pump.

In Figure 5, I have shown in detail the construction of the piston and lower end of the pump cylinder, comprising a piston head 36 loosely received within the pump cylinder and retained upon the reduced end of the piston rod by a cotter pin, or other fastening means 37. An opening 38 in the piston is normally closed by a valve 39 of leather, or other suitable material, held in place by a metal washer 40 which engages the shouldered end of the pump rod.

A cap 41 closes the end of the pump cylinder, such cap having formed therein a hole 42 covered by a flap valve 43 which is reinforced by a flat metal member 44 riveted thereto. The flap valve is retained on cap 41 by a bolt or rivet 45 in position to cover the opening 42.

Figures 6 to 9 inclusive, show a modified form of pump adapted for use with an exposed storage tank, wherein the upstanding pipe is made shorter to compensate for the increased over-all length of the pump and tank by reason of the location of the tank above ground.

In this modified form of my invention a threaded ring 50 surrounds an opening in the tank 51 and is welded, brazed or otherwise affixed to the tank. A T 52 is threaded at its lower end into the ring 50 and carries within it a pump cylinder 53 which extends downwardly into proximity to the bottom of the storage tank. The T, further, has an outlet 54 to which a flexible hose 55 is attached, and the pump cylinder has a hole 56 similar to that provided in the type of pump heretofore described for permitting run-back of excess gasoline after a dispensing operation.

A gland nut 57 is screw threaded into the upper end of the T and is internally threaded for the reception of a vertical upstanding pipe 58. In the lower end of the stand pipe

and above the discharge outlet 54 I have provided a loose stuffing box 59 which will permit the pump rod 60 to fall freely by gravity and without binding, but which will prevent a substantial quantity of gasoline from entering the upstanding pipe instead of being dispensed through the flexible hose. At its upper open end the upstanding pipe has a similar loose stuffing box 61 to prevent accidental overflow in case liquid should squirt in the upstanding pipe to this maximum level during a filling operation.

As is shown most clearly in Figure 8, the upper end of pump rod 60 is screw threaded and carries a support 62 for the flexible hose when it is not in use, and likewise a cap 63 to which a tubular hand grip is affixed in any suitable and well-known manner concentric with the upstanding pipe.

A coil spring 65 is preferably mounted between the gland nut 57 and the lower edge of hand grip 64, as is shown in Figures 6 and 7, to act as a shock absorber when the hand grip is reciprocated. Locking means to prevent unauthorized actuation of the pump is provided similar to that hereinbefore described.

In Figure 9 I have shown a slightly modified form of invention wherein a coiled spring 69 surrounds the lower end of the piston rod 60 and is adapted to be compressed between the piston and stuffing box 59 or gland nut 57 as the piston approaches the upper limit of its stroke to absorb shocks and eliminate impact.

In operation, reciprocation of the hand grip actuates the pump piston to lift gasoline or other liquids and to force the same through the flexible dispensing hose and into an automobile tank or other receptacle to be filled.

In this respect the pump combines the features of both lift and force pumps, since the gasoline or other liquid is initially lifted by reciprocation of the piston, and is subsequently forced to the point of dispensing by compressing it between the piston and stuffing box above the pump outlet. Due to the fact that the hose outlet is at a higher level than the point of its connection with the pump, and due to the pressure caused by upward stroke of piston during a dispensing operation, there is a tendency for the liquid being pumped to rise in the upstanding pipe.

The stuffing box immediately above the discharge outlet of the pump prevents all but a very little of the liquid to pass through and beyond it and such liquid as does pass flows back when pumping is discontinued and, by passing through the hole in the pump cylinder below the discharge outlet, finds its way back to the storage tank. Likewise, any gasoline or other liquid left in the flexible hose after a dispensing operation flows back into the pump cylinder and from there

through the vent hole provided, back to the storage tank.

From the foregoing it will be apparent that I have provided a practical, simple and effective dispensing pump which has the free motion of a simple lift pump and the necessary advantages of a force pump, accomplished by providing means to retain against overflow and the same means to utilize as a lubricant and packing, such portion of the pumped liquid as will leak through the loose stuffing box during a pumping operation, and by providing means for automatically draining back such leakage to storage tank and the same means for draining back excess liquid remaining in discharge apparatus after a pumping operation.

Having described my invention, what I claim is:

20 1. A lift dispensing pump comprising a cylinder, a pump rod and piston thereon reciprocable in said cylinder, a storage tank into which said cylinder extends, a discharge outlet communicating with the pump cylinder, a conduit leading from said discharge outlet to a point of dispensing at a higher level, an upstanding pipe above said discharge outlet forming a continuation of said pump cylinder extending a substantial distance 25 above the upper limit of the pump stroke, a stuffing box in said cylinder above the upward limit of the piston stroke and above the discharge outlet for preventing undue leakage of liquid therebeyond into the upstanding pipe, a vent formed in the wall of said cylinder in communication with the storage tank at a level below the pump discharge outlet, whereby liquid remaining undispensed after a pumping operation as well as 30 that which has leaked beyond the stuffing box will drain back to the storage tank, and a tubular hand grip concentrically encircling the upstanding pipe and attached to the piston rod, the said hand grip being freely slideable 35 over and guided by the upstanding pipe to effect reciprocation of the piston and consequent actuation of the pump.

2. In a dispensing pump, a liquid storage tank, a pump cylinder mounted thereon and 40 extending near the bottom thereof, a concentric second cylinder surrounding and attached to the top of said pump cylinder, forming a mounting therefor and also forming an enclosed annular space thereinbetween, the said annular space communicating with said storage tank, a vent in said 45 pump cylinder communicating with the top of said annular space, the said vent and the said annular space forming a drain-back for 50 excess liquid.

3. In a dispensing pump having a dispensing point above the discharge outlet of said pump, a pump cylinder, an upstanding pipe forming a continuation of said pump cylinder, the said upstanding pipe extend-

ing to a height above that of the said dispensing point, a discharge outlet positioned between said cylinder and said upstanding pipe and communicating with said pump, a second cylinder concentric with and surrounding said pump cylinder, the said second cylinder being attached to the top of said pump cylinder and forming an annular closed space thereinbetween, a vent in said pump cylinder communicating with the top of said annular space, the said vent and the said annular space forming a drain-back for 70 excess liquid. 75

4. A pump comprising a pump cylinder, a pump rod and piston thereon, reciprocable in said pump cylinder, a storage tank into which said pump cylinder extends, a discharge outlet communicating with said pump cylinder, a conduit leading from said discharge outlet to a point of dispensing at a higher level, an upstanding pipe above said discharge outlet forming a continuation of said pump cylinder extending a substantial distance above the said dispensing point, a stuffing box in said cylinder above the upper limit of the piston stroke and above the discharge outlet for preventing undue leakage of liquid therebeyond into said upstanding pipe, and a tubular hand grip concentrically encircling the said upstanding pipe and attached to the piston rod, the said hand grip being freely slideable over and guided by the upstanding pipe to effect reciprocation of the piston and consequent actuation of the pump. 80 85

5. A pump with the structure of claim 2, in which an upstanding pipe is mounted above and forms a continuation of said pump cylinder, the said upstanding pipe forming a guide for a tubular, concentric hand grip to which is attached the piston rod of said pump. 100 105

In testimony whereof, I have hereunto affixed my signature.

CLARENCE SCHOCK.
